UNITED STATES PATENT OFFICE.

JAMES B. HARRIS, OF BOSTON, MASSACHUSETTS, ASSIGNOR TO L. C. CHASE & COMPANY, OF BOSTON, MASSACHUSETTS.

FASTENER OR CLASP.

SPECIFICATION forming part of Letters Patent No. 739,673, dated September 22, 1903.

Application filed September 25, 1902. Serial No. 124,740. (No model.)

To all whom it may concern:

Be it known that I, JAMES B. HARRIS, a citizen of the United States, residing at Boston, in the county of Suffolk and State of Massachusetts, have invented an Improvement in Fasteners or Clasps, of which the following description, in connection with the accompanying drawings, is a specification, like figures on the drawings representing like parts.

This invention relates to fasteners or clasps which are adapted for various uses, such as holding together two parts of a garment, securing together the edges of a horse-blanket, or for use in any place where it is desired to detachably secure together two parts.

The clasp comprises two members, each of which has a shoulder adapted to engage the shoulder of the other member, and one of said members has a resilient holding-tongue adapted to engage the other member and hold the shoulders in engagement. Preferably, also, one of the members will be provided at its edges with holding-ears, which engage the sides of the other member and serve to assist in holding the members together. In this embodiment of my invention two members are each formed from a piece of sheet metal, and the shoulder on one of said members will be formed by making an aperture therein, the side of the aperture serving as a shoulder, while the shoulder on the other member will be formed by bending a portion of the metal to form a lateral projection, which is adapted to enter the recess in the other member. The resilient tongue is preferably made by making a substantially U-shaped cut in one member, and in order that the tongue may lie in substantially the plane of the two members I preferably bend or offset the inner portion of the member having the tongue, such offset portion receiving the end of the other member.

In the drawings, Figure 1 is a plan view of my improved fastener with the parts locked together. Fig. 2 is a view of the reverse side from that shown in Fig. 1, with the parts separated. Fig. 3 is a section on the line *x-x*, Fig. 1; and Fig. 4 is a view similar to Fig. 3, showing the way in which the parts are disengaged. The two members of the clasp are each preferably made from sheet metal and are desig-

nated by 3 and 4, respectively, each of said members being of such a construction, as will be presently described, that they may be stamped out.

The member 4 is provided with a suitable locking-shoulder 5, which is shown as extending transversely of said member and which is conveniently made by bending a portion of the metal to form the lip or shoulder 5. The other member 3 has a coöperating shoulder, and the two shoulders are held in locking engagement by means of a resilient tongue 8, which is attached to or formed integral with the member 3 and which when the two members are locked together engages the outer face of the member 4. I have herein illustrated said tongue as being formed by making a substantially U-shaped incision 9 in the member 3, thus leaving the tongue 8, under which the end of the member 4 may be inserted, and this construction permits of my employing the transverse edge 7 of the cut or incision as the shoulder on the member 3, it being understood that the width of the U-shaped cut is sufficient so that the opening made will receive the lip 5. In order that the two members may lie in substantially the same plane, even though the end of one overlaps the end of the other, I will preferably offset the inner end 10 of the member 3, as best shown in Figs. 3 and 4, to form a shoulder 11, against which the inner end 12 of the member 4 abuts when the said members are in operative locking position. One of the members, preferably the member 4, is provided at each edge with the holding-ears 13, which are adapted to engage the sides of the member 3, and thus prevent any relative lateral movement of the members. I will preferably construct the said ears at an inclination to the central line of the clasp and will construct the member 3 with correspondingly-inclined sides 14. By thus making the holding-ears 13 nearest together at the inner end of the member 4 and by forming the member 3 with the coöperating flaring sides 14 the ears 13 serve not only to prevent lateral displacement of either member, but also assist in preventing the members from becoming disengaged, as will be obvious. Assuming that the members are locked together, as in Fig. 3, they may be

easily disengaged by buckling said members, as shown in Fig. 4, the tongue 8 yielding sufficiently to allow the lip or shoulder 5 to become disengaged from the shoulder 7, when 5 said members may be separated longitudinally. In clasping the members together the end 12 of the member 4 will be inserted under the tongue between the same and the offset portion 10, when by raising the member 10 4 into substantially the position shown in Fig. 4 the said member may be moved longitudinally sufficiently to allow the lip or shoulder 5 to enter the aperture 7. Each of said members may have any suitable aperture 15 therein for the purpose of attaching the same to the garment or other material on which they are to be used, and, as illustrated, said apertures are designated by 17 and may be made in any suitable way, as by slitting said 20 member and bending the cut portion back upon the body thereof.

Although I have herein described one form of my invention, it will be obvious that the invention is not limited to the precise form 25 shown, but may be varied in various ways without departing therefrom. For instance, while I have herein illustrated and described my improved fastener as being made from sheet metal, I wish it understood that one of 30 the two parts of the device may be made of cast metal, if desired, or the ears 13 and lip 5 may be soldered or otherwise secured to the member 4 instead of being bent up from the body of said member, and many other such 35 similar changes made without departing from my invention.

Having described my invention, what I claim as new, and desire to secure by Letters Patent, is—

- 40 1. A fastener or clasp comprising two members, one having an aperture and a resilient holding-tongue between which and the body of said member the end of the other member is adapted to be received, and said latter
- 45 member having between its ends a lip projecting at right angles to the plane of said member, and adapted to be inserted through

said aperture and maintained therein by the resiliency of said tongue.

2. A clasp member provided with an aperture and having the apertured portion offset from the main portion, combined with another clasp member having a lip extending therefrom at right angles to the plane thereof and adapted to extend through the aperture, 55 the end of said latter member, when the two members are locked together, overlapping the offset portion of the first member and lying beneath the said tongue.

3. A clasp or fastener comprising two members, each formed from sheet metal, one member having a lip and holding-ears at its edges, and the other member having an aperture to receive said lip, and a resilient holding-tongue to hold said lip in engagement with the aperture, 65 said holding-ears engaging the sides of said last-named member.

4. A fastener or clasp comprising two members, one of said members having a lip and inclined holding-ears at its edges, and the 70 other member having a recess to receive said lip and a resilient holding-tongue to engage said first-named member and hold the lip in the recess, said inclined holding-ears engaging correspondingly-shaped edges of said last- 75 named member.

5. A fastener or clasp comprising two members, each formed of sheet metal, one member having a lip or projection and the other member having a recess to receive said projection, and a resilient holding device to hold 80 said members in engagement, one of said members having that portion thereof which is overlapped by the other member offset whereby the two members lie in the same 85 plane.

In testimony whereof I have signed my name to this specification in the presence of two subscribing witnesses.

JAMES B. HARRIS.
